RESPIRABLE GAS ADMINISTRATION APPARATUS

Arnold S. J. Lee, Belmar, N.J.

Application May 18, 1956, Serial No. 585,910

24 Claims. (Cl. 128—29)

This invention relates generally to apparatus for administering a respirable gas to a living subject, animal or human. More particularly, the invention relates to apparatus of this character adapted to automatically exert a form of control over the gas to thereby automatically render a bodily state of functioning of the subject in accordance with a pre-selected standard therefor.

This application is a continuation-in-part of my pending application Serial No. 484,460 filed January 27, 1955.

In connection with the description of the present invention, unless the context otherwise requires, the following words and phrases are to be taken in the senses indicated as follows. The phrase "respirable gas" is used to denote a fluid substance which may be an anaesthetic, therapeutic or experimental pure gas or mixtures of gases and/or vapors and/or gas-borne suspensions of liquid and/or solids. A respirable gas of any of these sorts will be referred to as an "input gas" when subject to inhalation by the patient, and as an "output gas" when the consequence of exhalation by the subject. More specifically, "output gas" will refer to that portion of the breathed out gases from the lungs of a patient which is last breathed out just before the patient starts to breathe in again; that is, the gaseous contents of the lung which were in intimate contact with the blood. In speaking of a property or properties of a gas, the word "property" is used to denote one or more of the sum total of the characteristics of the gas which serve to identify the given gas by differentiating it from all other gases. A referred to "property" may be physical or chemical in nature and may either represent a simple characteristic or a composite of characteristics which are all physical, all chemical or part physical and part chemical.

As further considerations, the word "analyze" is used to denote the action of continuously or semi-continuously measuring some substance in order to determine the value of one or more properties thereof. Also, the word "automatic" is used to denote continuous or semi-continuous operation of a device or system, essentially without the intervention of a human operator. The "bodily state of functioning of a subject" is to be taken to mean what is either usually considered a bodily function such as rate of respiration or a bodily condition such as depth of anaesthesia, or degree of balance between oxygen intake and metabolism.

While from the above it will be seen that the purview of the present invention comprehends a wide variety of forms of respirable gas administration apparatus, for convenience the shortcomings of the prior art in this field will be discussed in connection with that form of such apparatus which is used to produce anaesthesia in a living subject.

The usual form of anaesthetic administration apparatus depends upon a human operator for its control. In operating the apparatus the anaesthetist conventionally must rely entirely upon the data directly presented to his

2

senses in the form of external symptoms manifested by the subject. The anaesthetist first makes an evaluation based on this sense data of the current state of bodily functioning of the subject under anaesthesia. The anaesthetist then adjusts the flow of anaesthetic in accordance with this evaluation by him of the current "depth of anaesthesia" of the subject. If the depth of anaesthesia at any time is evaluated to be greater or less than the depth deemed desirable in view of the circumstances, the anaesthetist corrects for this discrepancy by manipulating his apparatus to change the current depth of anaesthesia in the appropriate direction.

From the above it will be seen that a number of factors may enter into the operation of a human controlled anaesthetic administration apparatus to render this operation an unreliable one for reaching the result desired. One such factor arises out of a possibly incomplete flow of data from the external symptoms of condition manifested by the subject to the sense receiving organs of the anaesthetist. Another such factor productive of unreliability may reside in the inexperience or other psychological inability of the anesthetist to correctly interpret the sense data received by him. A third such factor which should be mentioned is the total time lag occurring between the time that an incorrect depth of anaesthesia first occurs and the time when the depth is brought back fully to its desired value. This total time lag represents an accumulation of the respective times necessary for the incorrect depth of anaesthesia to be first manifested as an external symptom by the subject, the time necessary for the anaesthetist to first observe this symptom, the time required for interpretation of the symptom in the mind of the anaesthetist, and the time required, after the anaesthetist, has reached his mental conclusion of the proper corrective measure, for the anaesthetist to manually carry out this corrective measure. It will be seen that the factors contributing to this total time lag each represent an inherent slowness of response of the human body or brain, and that hence the time lag is unavoidable in the conventional anaesthetic administration technique.

It has been proposed heretofore to circumvent these shortcomings by providing an automatic anaesthetic administration system. This prior art system, however, is designed to determine the depth of anaesthesia of the subject by means of electric signals which are generated either within the body of the subject or as the result of a direct sensing, by probes or the like in contact with the body of the subject, or of the body functioning of the subject. Thus, the mentioned prior art system proposes to use electro-encephalographic or electrocardiographic signals as indications of the depth of anaesthesia of the subject. These signals are in themselves complex in form, and, moreover, the functional relation between the signals and the depth of anaesthesia is relatively complex. Accordingly, it is necessary in the mentioned prior art system to have an unusually complicated system of electric circuits and electronic tubes. This large-scale electrical organization is, of course, undesirable because of the expense, bulk, liability to failure, and difficulty of maintenance involved.

It is accordingly an object of the invention to provide respirable gas administration apparatus which is free of the disadvantages noted above.

It is another object of this invention to provide apparatus of the above noted character which operates by virtue of a relatively simple indication of the bodily state of functioning of the subject.

A further object of the invention is to provide apparatus of the above noted character requiring a mini-

mum number of electric circuit and other organizational components.

These and other objects are realized in accordance with the present invention by providing a fluid flow system carrying alternate flow of input and output gas to and from a living subject, and by providing an adjustable gas regulator mechanism connected in this system in regulating relation with the input gas to exercise a form of control thereover affecting the bodily state of functioning of the subject. Further, a gas analyzer means is connected in the mentioned fluid flow system in responsive relation with the output gas to automatically analyze the same by a mode of analysis providing signals indicative of the bodily response of the subject to the input gas. The signals so developed by the analyzer means are received by an automatic means which, responsive to these signals, adjust the regulator mechanism to automatically control the input gas to render the bodily state of functioning of the subject accordant to a preselected standard.

The invention may be better understood from the following detailed description of typical embodiments thereof, taken in conjunction with the accompanying drawings, in which:

Fig. 1 is a schematic diagram of a respirator-anaesthetizing apparatus constructed according to the invention;

Fig. 2 is a diagram of details of the apparatus of Fig. 1; and

Fig. 3 is a schematic diagram of an anaesthetic administration apparatus constructed in accordance with the invention.

In the description to follow it will be understood that analogous elements in the two embodiments will be designated by the same number, with such elements in the second embodiment being further designated by a prime suffix for the number. Further, analogous elements in the same embodiment will be designated by the same number with different letter suffixes.

Referring now to Figs. 1 and 2 which show a respirator-anaesthetizing apparatus for inducing forced breathing of a living subject along with administration of anaesthesia thereto, as a part of the apparatus there is shown a fluid flow system permitting alternate flow of input and output gas to and from a subject during, respectively, the inhalation and the exhalation phase of each recurring respiration of the subject. More specifically, this fluid flow system includes a gas distributing manifold 10 having an inlet port 11, an outlet port 12, and an exhaust port 13. An adapter 14 is coupled to manifold 10 for the purpose of guiding gas between the manifold and the respiratory tract of the subject.

The inlet port 11 has connected thereto a first conduit means comprised of a pair of conduits 20, 21 respectively communicating with sources (not shown) of anaesthetic gas (as, say, nitrous oxide at 50 p.s.i.) and a source of oxygen (at, say, 50 p.s.i.). The mentioned conduit means is also comprised of a third conduit 23 coupled directly at one end with the inlet port 11 and coupled at the other end through a mixer 24 with the conduits 20, 21.

The conduits 20, 21 in the usual manner have respectively interposed therein the manually set pressure regulators 26, 27. Each of these regulators is adapted to accept gas at high pressure from the source coupled therewith by way of the conduits, and to deliver this gas at some lower preset constant pressure essentially independent of the rate of gas flow. For indications of this lower preset pressure, the conduits 20, 21 are respectively equipped with the pressure gauges 28, 29.

The mixer 24 is a conventional gas flow device for mixing two gases in a constant preset proportion essentially independent of the rate of flow of the mixture of the gases. Thus, from the input of nitrous oxide and oxygen respectively received from the conduits 20, 21, 70, 75

the mixer 24 is adapted to flow into conduit 23 an anaesthetic mixture of fixed composition as, say, 70% nitrous oxide and 30% oxygen. By virtue of the construction of mixer 24, the percentage composition of this intermixture remains constant irrespective of pressure changes in conduit 23.

To provide for control of the input gas, the conduit 23 has interposed therein a variable regulator mechanism 30. In the present instance the input gas is controlled with regard to the specific property of the pressure thereof, and hence the regulator mechanism 30 is a variable pressure regulator which is adjustable in its regulating action by appropriate movement of a controller arm 31. In essence, the variable pressure regulator 30 receives gas flowing at medium pressure through conduit 23 from mixer 24, the regulator delivering this gas at some lower pressure determined by the position of control arm 31. The described regulator may be of the type commonly employed on acetylene and oxygen tanks for welding purposes, the regulator control arm being adapted to motor drive. The lower pressure output gas from the regulator is delivered into conduit 23 for flow thereof to inlet port 11 and from thence through manifold 10, adapter 14, and into the respiratory tract of the subject. For convenience in measuring the pressure of the regulated input gas, the portion of conduit 23 between regulator 30 and inlet port 11 may be equipped with the pressure gauges 32, 33 adapted respectively, to give exact pressure readings over a limited scale and approximate pressure readings over a wider scale.

The outlet port 12 has connected thereto a second conduit in the form of a conduit 40 running between the outlet port and an exit 41 permitting venting of gas in the conduit to the atmosphere. The conduit 40 has connected therein a gas analyzer means 42 (to be later described in further detail) and a sampling means 43 disposed in the conduit between the gas analyzer means and the outlet port 12. The sampling means in its essential components comprises a collapsible, but somewhat stiff and resilient tube 44 (fabricated from say, rubber), a larger diameter rigid tube 45 enclosing the major extent of tube 44 in a pressure-tight chamber, and valve means in the form of a check valve 46 disposed in conduit 40 between manifold 10 and tube 44 to permit flow of gas in the conduit only from the manifold towards the analyzer 42. The sampling means 43 may also desirably include a second check valve 47 disposed in conduit 40 between tube 44 and analyzer 42 to preclude any substantial backward flow of gas from the atmosphere through the exit 41 and thence into the analyzer.

As stated, the presently described apparatus is in part a respirator apparatus adapted to produce forced breathing in a subject. To this end the apparatus is provided with a two-way breathing valve wherein a valve plug 50 is adapted to be reciprocated back-and-forth between an upward seated position covering the exhaust port 13 and a lower seated position covering the inlet port 11. In this reciprocation the valve plug 50 is moved downwardly by a spring 51 disposed above the plug to act in compression thereagainst from a fixed support for the spring. Conveniently, the spring 51 may be positioned within an exhaust conduit 52 leading from exhaust port 13 to the atmosphere, the fixed support in this case being in the form of a bracket 53 extending radially inward of conduit 52 to hold the spring in alignment with the axis of the conduit. For better guidance of valve plug 50 in its reciprocating movement, preferably the compression spring 51 encircles an upper guiding stem 54 which extends from a juncture with plug 50 upwardly through bracket 53 by way of a bore (not shown) therein serving to constrain the stem to up and down movement only.

To provide upward movement in reciprocation of the valve 50, a fluid pressure cylinder 60 is mounted by an internal bracket 61 within and in alignment with the axis of a vertical section of conduit 23 adjacent to the inlet

port 11. The cylinder 60 contains within its bore a piston 62 connected to the valve plug 50 by a lower valve stem 63. Thus, in the presence of increased pressure in cylinder 60, sufficient force will be exerted on the piston to drive valve plug 50 against the compression of spring 51 to an upwardly seated position sealing exhaust port 13. Conversely, when the pressure in cylinder 60 is permitted to decrease, the compressive force of spring 51 overcomes the upwardly directed piston force. Accordingly, both valve plug 50 and piston 62 are driven downward with the respective consequences that the plug is seated to seal off inlet port 11 while the interior of cylinder is emptied of fluid by the downward movement of the piston.

Reciprocation of the described breathing valve is established by a timing means (Fig. 2) comprised of a constant speed motor 70, a breathing control cam 71a and sampling control cam 71b commonly driven by the motor 70, and a breathing control slide valve 72a and sampling control slide valve 72b actuated, respectively, from the cams 71a and 71b. Since the two valves mentioned are essentially similar in construction, it is only necessary for the most part to describe slide valve 72a, it being understood that, unless otherwise noted, the description of a given number element in valve 72a applies as properly to the element designated by the same number in valve 72b.

The slide valve 72a comprises a cylinder 75a, a piston 76a, slideable in tight-fitting relation within this cylinder, a cam follower 71a mounted on piston 76a to ride on cam 77a to thereby translate the variation in contour thereof into up and down piston movement, and a compression spring 78a acting on piston 76a to maintain cam follower 77a in firm contact with its cam. Within cylinder 75, the piston 76a is cut away circumferentially to have formed therein an annular groove 79a. The groove 79a performs the function of furnishing a fluid flow coupling between either a middle conduit 85a and a lower conduit 86a coupled to a high pressure fluid source, or between the middle conduit 85a and an upper conduit 87a venting to the atmosphere. The middle conduit 85a is itself coupled with the interior of driving cylinder 60 for the breathing valve.

As stated, the sampling control valve 72b is essentially similar in construction to the breathing control valve 72a with the following exceptions. First, the cam 71b which operates valve 72b is of different contour than the cam 71a for valve 72a. Second, in valve 72b it is the upper conduit 87b which is connected to the high pressure fluid source, and it is the lower conduit 86a which opens to the atmosphere. Third, the middle conduit 85b of valve 72b furnishes a fluid flow coupling from the valve to the interior of the outside tube 45 (Figures 1 and 2) in the sampling means 43.

Considering for the time being the action of breathing control valve 72a only, the contour of the cam is subdivided into a lowered arc 90 of smaller angular extent and a raised arc 91 of larger angular extent. When cam follower 77a rides in lower arc 90, the piston 76a positions groove 79a to provide for flow of high pressure fluid from conduit 86a through conduit 85a to the interior of cylinder 60. The valve plug 50 will be accordingly moved upward to uncover inlet port 11 and to seal exhaust port 13. Responsive to this valve plug movement, a flow of input gas under slight pressure will ensue from conduit 23 into manifold 10 and from thence through adapter 14 into the respiratory tract of the subject. Within the respiratory tract, the slight pressure of the input gas causes the subject's lungs to expand, the net effect being an inhalation by the subject which is forcibly induced.

The changeover from inhalation to exhalation in the forced respiration of the subject is effected by rotation of the cam 71a raising the cam follower 77a up upon the arc 91 of the cam contour. Piston 76a is accord-

ingly moved upward to disconnect the interior of cylinder 60 (Figure 1) from the fluid pressure conduit 86a (Figure 2) and to establish an exhaust path for the cylinder through conduit 85a, valve groove 79a, and exhaust conduit 87a. In consequence, the compression spring 51 acts, as described, to exhaust fluid from cylinder 60 and to move valve plug 50 downward so that the exhaust port 13 and the inlet port 11 of manifold 10 are respectively uncovered and sealed. With the respective changes in condition taking place as to these two ports, the lungs of the subject are free of the pressure effect of the input gas. Freed of this pressure effect, the subject's lungs contract elastically to exhale output gas through adapter 14, manifold 10, exhaust port 13, and exhaust conduit 52.

It is thus seen that the described apparatus develops recurring forced respirations of the subject consisting alternately of inhalations and exhalations. An apparatus performing this function is commonly used, for example, where for medical reasons it is desirable to anaesthetize a subject who has been completely paralyzed by the action of a drug or the like.

It is well known, in the normal physiological control of respiration, that the amount of air taken into a subject's lung is so adjusted by the subject's body that the carbon dioxide level remains constant at the subject's physiological level. The carbon dioxide normally present exerts a tension of 40 mm. of mercury. This amount of air is then usually adequate to provide a proper oxygen availability to the blood in the subject's lungs. In natural respiration, this amount of air taken in is ordinarily controlled by a physiological process wherein involuntary nerve centers of the human body respond to the percentage of carbon dioxide in the blood stream to adjust the rate and/or depth of respiration. Thus, where the carbon dioxide in the blood stream increases, the mentioned nerve centers act to increase the involuntary depth and rate of breathing or to create a feeling of shortness of breath in the subject. Also, when the carbon dioxide in the blood stream decreases, the mentioned nerve centers adjust the involuntary breathing of the subject to the proper rate and depth.

It will be evident, however, that with complete paralysis of the subject, the described involuntary self-adjustment of the state of bodily functioning of the subject is no longer effective because of paralysis of the lungs. Unless the carbon dioxide tension is carefully controlled by accomplishment of the required tidal exchange, important consequences result. Thus, reducing the alveolar tension to say 20 mm. mercury induces a general vasoconstriction, especially in the cerebral blood vessels and diminishment of the respiratory drive as the respiratory center is made less sensitive. Still lower carbon dioxide tension, such as 10 mm. of mercury, produces syncope or fainting. Higher carbon dioxide arterial blood tensions than normal, such as about 50 mm. of mercury, cause increased respiratory drive, dilate the cerebral blood vessels, and often cause increased blood pressure and pulse rate. It is, accordingly, necessary that some artificial substitute be provided for the involuntary control over respiration normally provided within the body of the subject when the subject is anaesthetized.

In accordance with the present invention, to provide for this substitute control over respiration, the cam 71b is shaped in contour to have radially raised and lowered portions 100 and 101 which are respectively of such angular extent and phase with respect to the contour of cam 71a (which establishes the periods of inhalations and exhalations) that the cam follower 77b rides on lowered arc 101 only during a short interval at the end of each exhalation. Thus, during a major interval of a respiration induced in the subject, the piston 76b of the sampling control valve is positioned upward to establish a fluid flow coupling from pressure conduit 87b through valve groove 79b and conduit 85b to the interior of

the outside tube 45 of sampling means 43. In consequence, there is produced within this outside tube a high pressure condition which collapses the inner tube 44 during inhalation by the subject and during most of the time of exhalation thereby. At the end of exhalation, however, the cam follower 77b drops momentarily into the lowered arc 101 of cam 71b with the consequence that piston 76b drops downward to vent the interior of tube 45 to the atmosphere through conduit 85b, valve groove 79b and exhaust conduit 86b. With the pressure within tube 45 so released, the inner tube 44 springs back into uncollapsed shape to thereby produce a vacuum in its interior. Responsive to this vacuum, the check valve 46 opens to permit a sample of end-of-exhalation output gas to flow from manifold 10 to within tube 44. When, at the beginning of the next inhalation, the cam follower 77b is once again raised up on the arc 101 of cam 71b, the resulting higher pressure condition re-established within tube 45 causes the tube 44 to again collapse to thus force the contained sample of end-of-exhalation output gas through the check valve 47 to flow through the analyzer 42.

As is known, over the whole interval of an exhalation, the carbon dioxide content of the output gas undergoes a wide fluctuation in value, the spread in values in this fluctuation not being of substantial significance as a measure of the carbon dioxide level in the blood of the subject. Considering the succession of individual fluctuations occurring from exhalation to exhalation, however, there may be discerned therein a trend in value representing a measure of the carbon dioxide content of the blood stream. The course of this trend may be established in various ways, as by taking the average value of each fluctuation or the highest value thereof, or the lowest value thereof, or the value thereof at some fixed phase in time of the exhalation period. It has been found, however, that a very satisfactory measure is obtained of richness of the blood in carbon dioxide if a sampling means like that described is utilized to sample the output gas by taking end-of-exhalation samples thereof which are, of course, alveolar gas. Since no carbon dioxide is administered, it has a zero concentration in the input gas. Therefore, the difference between arterial carbon dioxide concentration and venous carbon dioxide concentration will be small, even when there are appreciable areas of atelectasis. The carbon dioxide output gas tension accordingly will about equal the arterial blood carbon dioxide tension. Since the output gas, i.e., the last portion of the expelled or alveolar gas, normally has a carbon dioxide tension of 40 mm. of mercury the arterial tension in carbon dioxide will be about the same figure.

The output gas samples which pass through analyzer 42 are analyzed therein for the specific property of the output gas of its carbon dioxide content. Preferably the analyzer 42 is in the form of an infra-red spectrophotometer analyzer such as is described in further detail on pages 1021 and 1036 of "Medical Physics," volume II, by Otto Glasser and published by the Yearbook Publishers, Inc., Chicago, Illinois. An analyzer of this type is adapted to provide on an output lead 105 an electrical voltage signal which is roughly proportional to (or, at least in direct correspondence to) the percentage of carbon dioxide in the gas mixture fed to it. For the purpose of generating such signal, the analyzer has a self-contained amplifying system.

The analyzer signals on lead 105 are fed to an automatic means which responds to these signals to automatically adjust the setting of or maintain a given setting of the variable pressure regulator 30. This automatic means may take the form in a broad sense of a means for generating a reference signal representing a preselected value for the end-of-exhalation carbon dioxide content of the output gas (and thus a preselected value for the richness of carbon dioxide in the blood

stream), a means for comparing the analyzer signals in value with this reference signal, and a means responsive to a change in value of the analyzer signals away from the reference signal for adjusting the pressure regulator 30 to ultimately cause the analyzer signals to follow the reference signal. While the reference signal may, of course, be a signal which changes in value over time in a preselected manner, in most cases it suffices for the reference signal to have a steady value over time in the absence of manual intervention to change the value of the signal.

As a specific example, the automatic means referred to may take the form shown in Figure 1 wherein the reference signal is generated as the steady voltage output of a reference signal generating means 109. This means may take such form that the output thereof appears on a movable tap 110 of a potentiometer resistor 111 connected across a voltage source shown as the battery 112. As stated, this reference signal represents a preselected value for the end-of-exhalation carbide dioxide content of the output gas, the signal thus being indicative of a preselected value for the richness in carbon dioxide in the blood stream of the subject being administered to by the apparatus. Selection of such value or a change in the selected value from one to another value is effected by manually sliding tap 110 over resistor 111. A meter 113 may, for convenience, be connected with a signal carrying lead 114 from tap 110, the meter indicating the voltage of the reference signal.

The analyzer signals on lead 105 and the reference signal on lead 114 are fed as respective inputs to a servo system such as say, a servo-system comprised of the components manufactured by the Brown Instrument Division of the Minneapolis Honeywell Company of a continuous balancing amplifier (catalog number 351921 and a balancing motor (catalog number 76750-1). As shown in Figure 1 this servo system is comprised essentially of a servo amplifier 119 (consisting of a subtracting chopper amplifier 120, and a power amplifier 121) and a servo motor 122 in the form of a two-phase induction motor characterized by a first phase winding 123 and a second phase winding 124 which is spatially in quadrature relation with phase winding 123. The phase winding 123 may be energized in a conventional manner from an alternating current power source 125, which also acts, as will now be described, as a synchronizing signal source for the subtracting chopper amplifier 120.

The subtracting chopper amplifier 120 is of a well known type, which, in the presence of a difference in voltage between the analyzer signals and the reference signal inputs, is adapted to produce an error signal form of the analyzer signals. This error signal represents by its amplitude and polarity the amplitude and polarity of the voltage difference between the input analyzer and reference signals. As another function, the subtracting chopper amplifier 120 is adapted to render this error signal of alternating form by chopping the error signal at the frequency and phase of a synchronizing signal received by the amplifier. In the present instance, this synchronizing signal is a signal originating with alternating source 125 which is thereafter impressed with a 90° phase shift by a phase shifting device 126. Accordingly, if there is no difference in voltage between the analyzer signals and reference signal inputs to amplifier 120, the amplifier will produce zero output. On the other hand, a voltage difference between the input signal will be represented at the output of the amplifier by an alternating error signal of the same frequency as the current which excites phase winding 123. In dependence on whether the analyzer signals are greater or less than the reference signal, the error signal output from amplifier 120 will have one or the other of opposite phases, both of these phases being electrically displaced 90° from the phase of the current energizing winding 123.

The error signal output from amplifier 120 is fed to

the power amplifier 121 which amplifies the signal by an amount sufficient to provide for proper energization of the phase winding 124, the amplified error signal being applied to this winding. As is known, the motor 122 will not rotate when only phase winding 123 is energized. In the presence, however, of an error signal which energizes winding 124 in 90° phase relation to the current in winding 123, the motor 122 will rotate in one direction or the other in dependence on whether the error signal leads or lags by 90° the exciting current for winding 123.

The mechanical angular output of motor 122 is coupled to the control arm 31 of pressure regulator 30 by a linkage consisting of the arms 128 and 129. There is thus established in the respirator apparatus a closed loop causal sequence wherein a series of responses are interrelated as follows:

If the quantity of gaseous intake by the subject is lower than optimum, this fact is manifested in the physiological functioning of the subject by an increase in the carbon dioxide content of the blood stream. The analyzer 42 detects this carbon dioxide increase to cause the analyzer signal on lead 105 to shift away in voltage value from the reference signal on lead 114. The described servo system responds to this shift to adjust pressure regulator 30 to a setting which appropriately increases the pressure of the input gas fed to the subject. The subject responds to this increased pressure by a deeper forced inhalation. Since in this event the subject will also exhale more deeply, the carbon dioxide content of the subject's blood stream is diminished until the proper balance is once again restored between the quantity of gaseous intake and the carbon dioxide level of the subject. Conversely, if the quantity of gaseous intake by the subject is greater than optimum, the carbon dioxide content of his blood stream drops to create a difference between the analyzer signals and the reference signal to thus stimulate the described servo system to adjust the regulator 30 to decrease the pressure of the input gas fed to the subject. As a result, the forced respiration of the subject will be less deep, and the carbon dioxide content of the blood stream will rise to its proper level.

By means of this invention actual tests have maintained arterial blood carbon dioxide tension within 3 mm. of 40 mm. of mercury, the normal tension, for as long as three hours during surgical operations.

Instead of controlling respiration on the basis of carbon dioxide, the same thing may be accomplished by analyzing the oxygen content of the output gas and adjusting the oxygen or air given to the patient to maintain a normal arterial oxygen tension of about 105 mm. of mercury. The alveolar gas oxygen tension is normally about 110 mm. of mercury. The gradient between arterial and alveolar oxygen tensions is ordinarily about 5 mm. of mercury although errors in ventilation or diffusion may make for increases in the gradient. For the purpose of controlling respiration by oxygen analysis it is convenient to base the respiration control system on the normal venous oxygen tension of 40 mm. of mercury. Using this as the standard, a sample of output gas taken at the end of exhalation may be analyzed for oxygen content, compared with the standard and the input gas adjusted accordingly to maintain proper administration of oxygen. In such a system it is generally desirable to maintain an input oxygen tension of below 250 mm. of mercury since non-apparent errors may arise due to the characteristics of hemoglobin-oxygen dissociation.

Referring now to Figure 3, there is shown therein another example of the present invention in the form of an apparatus for administering anaesthetics to a subject. In this apparatus a manifold 10' has an inlet port 11', and an outlet port 12', and has joined therewith an adapter 14' in the form of a mask which fits over the nose and mouth of the subject. The adapter 14', as before, performs the function of furnishing a guideway for a flow of

gas between manifold 10' and the respiratory tract of the subject.

Coupled with the inlet port 11' is a first conduit means consisting of the separate conduits 20', 21', respectively coupled to a source of anaesthetic gas (as, say, cyclopropane) at above atmospheric pressure and a source of oxygen at above atmospheric pressure. The first conduit means is also comprised of a mixing conduit 130 coupled between a gas flow junction 131 and a junction of the conduits 21', 20', a conduit 23' coupled directly to the inlet port 11', and a breathing purifier 132 coupled in terms of gas flow between the gas flow junction 131 and the conduit 23'. The conduits 20', 21' have conventional rate of flow meters 135, 136, respectively connected thereto to regulate the flow of gas in each of these conduits. Further control over these gas flows is afforded by a manually operated needle valve 137 connected in conduit 21' and by a needle valve 138 in conduit 20' which permits a flow of cyclopropane therethrough in accordance with the setting in adjustment of a control arm 139 for the needle valve.

The cyclopropane in conduit 20' and the oxygen in conduit 21' flow into conduit 130 to be intermixed therein to form the input gas administered to the subject. This input gas has a relative percentage composition of pure anesthetic gas and of oxygen gas wherein the relative percentages of these two components are determined by the respective settings of the needle valves 137 and 138. From conduit 130 the input gas flows through junction 131, purifier 132, conduit 23', inlet port 11', manifold 10', and adapter 14' into the respiratory tract of the subject during inhalation thereby.

The outlet port 12' for the manifold has connected therewith a second conduit means in the form of a conduit 40' running between the outlet port and the gas flow junction 131. The output gas exhaled by the patient is conveyed by conduit 40' from manifold 10' to junction 131 from whence the output gas passes through the purifier 132 which is a carbon dioxide absorber. The output gas after being freed of most of its carbon dioxide content by passing through the purifier is recirculated back through conduit 23' to the subject. In this connection it will be noted that while there may be a considerable volume of circulating gas, the quantity of gas flowing out of conduit 130 just balances with the quantity of gas which is inhaled and absorbed by the subject. Thus there is a flow of input gas to the subject although this flow is accomplished through the intermediary of a volume of circulating gas.

To assure a proper gas circulation of the sort described, the apparatus is provided with valve means consisting of the check valve 140 disposed in conduit 23' to permit gas flow only toward inlet port 11' and also the check valve 141 disposed in conduit 40' to permit gas flow in this conduit only away from the outlet port 12'.

The apparatus of Figure 3 as so far described (with the exception of the mechanically adjustable needle valve 138) represents a closed circle anesthesia system such as is disclosed on page 24 of the afore-mentioned text by Otto Glasser. Such system is characterized by continuous circulation of the anesthetic gas around the loop formed by conduit 23', manifold 10', conduit 40', and purifier 132. The fraction of oxygen and cyclopropane absorbed by the subject from the circulating anesthetic mixture during inhalation is continuously replenished from the oxygen and cyclopropane flows in the conduits 21' and 20'. Further, in the circulating mixture, the waste product of carbon dioxide exhaled by the subject is continuously removed by a soda lime mixture in the purifier 132.

To permit closed loop circulation of the anesthetic mixture without the introduction of pressure conditions varying widely from those normal for respiration, the described apparatus includes a flaccid balloon 145 connected to the purifier 132. As the pressure in the circulating mixture rises and falls, the balloon 145

responsively expands and contracts to tend to maintain the pressure at atmospheric value.

When a subject is under anaesthesia, the depth of anaesthesia of the subject at any time, although usually ascertained by indirect symptoms thereof such as rate of respiration or rate of heartbeat, is in fact in direct relation to the percentage content of anesthetic gas in the blood stream of the subject. This blood stream content of anesthetic gas is reflected in the percentage of anesthetic gas appearing in the output gas exhaled by the subject.

As in the case of the carbon dioxide content of the output gas in the Figure 1 apparatus, however, the content of anesthetic gas in the output gas of the Figure 3 apparatus is characterized by a short term fluctuation in value over the period of each exhalation and by a trend of the fluctuations from exhalation to exhalation. Of these two factors, only the trend in anesthetic gas content from exhalation to exhalation is a satisfactory indication of the depth of anesthesia of the subject. Accordingly in the operation of the Figure 3 apparatus, to automatically bring the subject to or maintain the subject at a preselected depth of anesthesia, it is necessary that the trend in this percentage content be dissociated from the short term fluctuations therein.

To provide for automatic control of depth of anesthesia, the apparatus of Figure 3 includes a gas analyzer 42' connected in conduit 40' between the outlet port 12' of the manifold and the mentioned gas flow junction 131. The analyzer 42' may be an analyzer generally like the analyzer 42 of the Figure 1 apparatus except that analyzer 42' is adapted to analyze the output gas for a percentage content of cyclopropane rather than for a percentage content of carbon dioxide. It will be noted that the aforementioned text by Otto Glasser describes on page 1024 and on page 1036 the details of analyzers suitable for both such purposes.

As is to be expected, cyclopropane analyzer 42' represents the outcome of its analysis for this gas in the form of electrical signals.

The Figure 3 apparatus, like the Figure 1 apparatus includes an automatic means responsive to the signals of the analyzer for adjusting the regulator mechanism for the input gas to produce a preselected bodily state of functioning of the subject. Thus in the present instance the automatic means adjusts the setting of the adjustable needle valve 138 to govern the relative percentages of cyclopropane and oxygen injected into the circulating anesthetic mixture to thus bring the subject to or maintain the subject at a preselected depth of anesthesia. This automatic means is analogous to that previously described for the Figure 1 apparatus in that it is comprised of the components of a reference signal generating means 109', a subtracting chopper amplifier 120', a power amplifier 121', a servomotor 122' and a phase shifter 126', the mentioned components being constructed and mutually cooperative in a manner alike to the corresponding components of the Figure 1 apparatus. The automatic means of the Figure 3 apparatus differs, however, in one important respect, now to be described, from the automatic means of the Figure 1 apparatus.

It will be noted in the Figure 3 apparatus that the conduit 40', which serves among other uses to couple the cyclopropane analyzer 42' in responsive relation with the output gas, permits the free flow of output gas during the whole of each exhalation period by the subject. This free flow of output gas in conduit 40' is preferable in a closed loop anesthetic administering system (of which conduit 40' represents a section of the loop) in order to avoid the setting up of pressure stresses in the circulating anesthetic mixture as a result of interruption of the free circulation. It follows, however, that with free flow of output gas through conduit 40' during the whole of each exhalation, the output signals from analyzer 42' will also extend over the whole of each

exhalation. Thus these analyzer signals will, as the unmodified output of the analyzer, be indicative of both the intra-exhalation fluctuations and the inter-exhalation trend in percentage content of anesthetic gas in the output gas, rather than being the desired indication of the trend in percentage content dissociated from the fluctuations thereof.

For the purpose of rendering the Figure 3 apparatus responsive primarily to this trend in percentage content, the apparatus is provided with a sampling means in the form of a pressure sensitive switch 150 and a sampling relay 151. Considering first the switch, this component comprises a gas tight container 152, a resilient diaphragm 153 of electrically conducting material dividing the interior of container 152 into left hand and right hand gas tight chambers 154, 155, a contact 156 mounted on diaphragm 153, and a pair of fixed contacts 157, 158 respectively located within chambers 154 and 155 to respectively close with contact 156 when diaphragm 153 is in an expanded and a contracted condition. Normally diaphragm 153 is in contracted condition so that the contact 156 of the diaphragm is electrically closed with the right hand fixed contact 158.

For control of the expansion and contraction of diaphragm 153, the left-hand chamber 154 of container 152 is connected by a conduit 160 to a junction 161 of this conduit with a section of conduit 40' between manifold 10' and analyzer 42'. The right-hand chamber 155 of container 152 is connected by a conduit 162 with the gas flow junction 131. During the major time interval of a respiration by the subject, the fluid pressure in conduit 40' at the junction 161 is either greater than or substantially equal to the fluid pressure at junction 131. These relative pressure conditions are duplicated by the relative conditions of the pressures within chambers 154 and 155 to maintain diaphragm 153 in contracted state to thus keep contact 156 closed with contact 158. At the beginning of inhalation, however, the initial indrawing of breadth by the subject reduces the pressure at junction 161 below the pressure at gas junction 131, the mentioned pressure reduction being augmented by the action of check valve 141 in preventing flow of gas from junction 131 towards the other junction. The resulting pressure reduction in chamber 154 of container 152, relative to the pressure in chamber 155 thereof, causes diaphragm 153 to expand so that contact 156 moves leftward to momentarily close with contact 157. At this time the output gas within analyzer 42' is that fraction of the output gas expelled by the subject substantially at the end of exhalation. Of course, the described momentary pressure drop is speedily relieved by flow of gas from conduit 23' through manifold 10' into conduit 40', the diaphragm 153 hence recontracting after a short interval to break the contact of elements 156, 157 and to reestablish the contact of elements 156 and 158.

The contacts 156 and 158 are in a condenser charging circuit consisting, in series connection, of contact 156, the diaphragm 153, a capacitor 165, a charging source shown as the battery 166, a resistor 167, and the contact 158. When contacts 156 and 158 are closed, the condenser 165 charges up through the described circuit to output voltage value of the battery 166. The contact 156 is also in a discharging circuit for capacitor 165, this discharging circuit consisting of the upper side of the capacitor, the diaphragm 153, contact 156, contact 157, a relay winding 170 of sampling relay 151, and a return through ground to the lower side of capacitor 165. When contact 156 momentarily closes with contact 157, the previously charged capacitor discharges through the circuit just described to produce a momentary energization of relay winding 170. This energization occurs at the beginning of inhalation when, it will be recalled, the output gas within analyzer 42' is substantially of end-of-exhalation nature.

The relay winding 170 of sampling relay 151 operates

when energized to close together the movable and fixed contacts 171, 172 of a switch disposed in circuit between the output of power amplifier 121' and the phase winding 124' of servomotor 122'. Accordingly, the signals which operate the servomotor are rendered indicative of the specific value at the end of exhalation of the percentage content of anesthetic gas in the output gas. The servomotor 122' in its action of adjusting needle valve 138 is thus made responsive to the inter-exhalation trend in the mentioned percentage content rather than to the intra-exhalation fluctuations thereof. From the foregoing the operation of the apparatus in Figure 3 will be largely self-evident. The reference signal generating means 109' provides a reference signal of a value representing a pre-selected depth of anesthesia for the subject. If the subject is or becomes under-anesthetized with respect to this depth, the resulting lack of cyclopropane in the blood stream of the patient will be manifested at the end of exhalation by a low or lowered percentage content of cyclopropane in the output gas. This under value of cyclopropane has the effect, by the respective actions of the analyzer 42', the subtracting chopper amplifier 120, the power amplifier 121, the sampling relay 151 and the servomotor 122', of producing a setting in adjustment of needle valve 138 to increase the flow of cyclopropane through conduit 20' to thereby bring the subject to or restore the subject to the preselected depth of anesthesia. In like manner, if the subject is or becomes over-anesthetized, the excess of cyclopropane in the blood stream of the subject initiates a sequence of events in the operation of the apparatus which brings the subject to or restores the subject to the preselected depth of anesthesia.

In the administration of anesthetic gases such as ethyl ether, chloroform and cyclopropane, which are essentially not consumed or changed by the body, concentrations of such gases are usually administered which the patient may well tolerate until anesthetized to the desired level, after which time the administration must be continued at such concentrations so as to maintain an equilibrium between the anesthetic input and anesthetic output. The apparatus of this invention maintains the necessary equilibrium. For first plane anesthesia (surgical), or slightly lighter, the following concentrations may be used:

Substance	Input Gas Conc., Percent by Vol.	Arterial Blood Conc., mgm./100 cc.
Ethyl ether	2.5	100
Chloroform	0.5	0.6
Cyclopropane	6.0	34.0

It is assumed for such concentrations to create the desired equilibrium that the so-called "ventilation/perfusion ratio" is about unity, i.e., there are no significant portions of the lungs which are either perfused by blood but not ventilated by gas (as in atelectasis or obstructed breathing) or ventilated by gas but not perfused by blood (emphysema). Since the arterial anesthetic blood tension is the controlling determinant of the depth of anesthesia where the "ventilation/perfusion ratio" is about unity the anesthetic partial pressure in the input gas is the controlling determinant of the depth of anesthesia. Where the "ventilation/perfusion ratio" is not close to unity, the input concentration of the anesthetic gas must be raised in accordance with the defect to maintain the same arterial anesthetic blood level.

The administration of an anesthetic gas is regulated by the concentration of such gas in the output gas or exhalation as determined by the analyzer, which then signals the automatic means for adjusting the needle valve for controlling input of the anesthetic gas. The automatic means is pre-set and controllable. If the analyzer indicates a concentration of anesthetic in the output gas

above or below that required for the desired anesthesia, the automatic means responds thereto and causes the needle valve to increase or decrease the concentration of anesthetic in the input gas. The concentrations of typical anesthesia gases which, when present in the output gas, give various depths of anesthesia are as follows:

10	Depth of Anesthesia		
	Analgesic	Percent	
		Percent	Percent
15	Diethyl ether	2	5
	Chloroform	0.2	0.8
	Cyclopropane	5	15
	Ethyl chloride		25
	Vinyl ether	3	
	Nitrous Oxide	0.2	2
	Trichloroethylene	65	80
		0.3	0.5
			0.8

When one of these gases is administered an analyzer is used which is capable of analyzing for the particular anesthetic gas administered. Thus, a chloroform analyzer is used when chloroform is administered, and an ethyl ether analyzer is used when ethyl ether is the anesthetic gas administered.

20 In cases where the anesthetic induces anesthesia while the patient continues to breathe, as with cyclopropane, not only may the administration to one patient of cyclopropane be regulated by this invention but, also, the total volume exchange of respired gases. This is accomplished by analyzing alternate exhalations for cyclopropane and either oxygen or carbon dioxide. By arranging the apparatus in a suitable manner each exhalation may be analyzed for the content of both such gases. The sampling arrangement may be set up as desired.

25 The above-described embodiments being exemplary only, it will be understood that the present invention comprehends organizations differing in form or detail from the presently described embodiments. Accordingly, the invention is not to be considered as limited save as is consonant with the scope of the following claims.

I claim:

1. Apparatus for administering a respirable gas to a living subject comprising, a fluid flow system providing 45 for alternate flow of input and output gas to and from said subject during the inhalations and exhalations thereof, adjustable gas regulating mechanism connected in said system in regulating relation with said input gas to thereby quantitatively control a bodily state of functioning of said subject, gas analyzer means connected in said system in responsive relation with said output gas, said apparatus being adapted by automatically analyzing said output gas to produce signals indicative of the bodily response of said subject to said input gas, and automatic 50 means responsive to said signals for adjusting said regulating mechanism to render said bodily state of functioning of said subject accordant with a preselected standard therefor.

2. Apparatus as in claim 1 wherein said apparatus is 55 a respirator apparatus adapted to produce forced respiration of said subject.

3. Apparatus as in claim 1 wherein said apparatus is an anaesthetic administration apparatus.

4. Apparatus for administering a respirable gas to a living subject comprising, a fluid flow system providing 65 for alternate flow of input and output gas to and from said subject during the inhalations and exhalations thereof, adjustable gas regulating mechanism connected in said system in regulating relation with said input gas to quantitatively control a property thereof serving to quantitatively control a bodily state of functioning of said subject, gas analyzer means connected in said system in responsive relation with said output gas to automatically analyze the same for a property thereof characterized in 70 quantitative value by short term fluctuations and a longer

term trend, said fluctuations and trend being manifested, respectively, within individual exhalations and from exhalation to exhalation, and being, respectively, extraneous to and indicative of the bodily response of said subject to said input gas, said analyzer means being adapted to generate signals as the outcome of said analysis, sampling means operable by repetitively sampling said fluctuations to render said analysis indicative in terms of said signals of said trend dissociated from said fluctuations, and automatic means responsive to said signals for adjusting said regulating mechanism to produce a following by said trend of a preselected standard of value therefor, said apparatus being accordingly adapted to automatically render said bodily state of functioning of said subject accordant with a preselected standard therefor.

5. Apparatus as in claim 4 wherein said sampling means establishes said trend by rendering said analysis indicative in terms of said signals of an end-of-exhalation sampling of said output gas.

6. Apparatus for administering a respirable gas to a living subject comprising, a fluid flow system providing for alternate flow of input and output gas to and from said subject during the inhalations and exhalations thereof, adjustable gas regulating mechanism connected in said system in regulating relation with said input gas to quantitatively control a property thereof serving to quantitatively control a bodily state of functioning of said subject, gas analyzer means connected in said system in responsive relation with said output gas to automatically analyze the same for a property thereof indicative of the bodily response of said subject to said property of said input gas, said analyzer being adapted to generate signals indicative of the value of said property of said output gas, means adapted to develop a reference signal representing a preselected standard of value for said last-named property, means for comparing said analyzer signals with said reference signal, and means responsive to a change established by said comparison of said analyzer signals away from said reference signal for adjusting said regulating mechanism to restore said analyzer signals to conformity with said reference signal, said apparatus being accordingly adapted to automatically render said bodily state of functioning of said subject accordant with a preselected standard therefor.

7. Apparatus for administering a respirable gas to a living subject comprising, a fluid flow system providing for alternate flow of input and output gas to and from said subject during the inhalations and exhalations thereof, adjustable gas regulating mechanism connected in said system in regulating relation with said input gas to quantitatively control a property thereof serving to quantitatively control a bodily state of functioning of said subject, gas analyzer means connected in said system in responsive relation with said output gas to automatically analyze the same during said respirations for a property thereof indicative of the bodily response of said subject to said property of said input gas, said analyzer being adapted to generate electric voltage signals indicative of the value of said property, of said output gas, electrical means for developing an electrical reference signal having a steady voltage representing a preselected value for said property of said output gas, servo-amplifier means responsive to inputs of said analyzer signals and said reference signal for producing an output of an error signal indicative of a change in voltage of said analyzer signals away from said reference signal, and servo-motor means responsive to said error signal for adjusting said regulating mechanism to restore said analyzer signals to equality with said reference signal by the causal sequence described herein as following on said adjustment, said apparatus being accordingly adapted to automatically render said bodily state of functioning of said subject accordant with a preselected standard therefor.

8. Apparatus as in claim 7 wherein said electrical means permits adjustment between one value and another of the steady voltage of said reference signal.

9. Apparatus as in claim 7 wherein said servo-motor means is an electric motor adapted to receive a first input of alternating current at a fixed phase and frequency, said servo-amplifier means is synchronized by said current to develop an alternating error signal at said frequency and of opposite phases for oppositely going changes of said analyzer signals away from said reference signal, and said motor is connected with said servo-amplifier to receive any error signal developed thereby as a second input to said motor, said motor being adapted to rotate in opposite directions in the presence, respectively, of alternating error signals of opposite phases.

10. Apparatus for furnishing a living subject with respirable gas in the nature of input gas and output gas during, respectively, the inhalations and exhalations of said subject, said apparatus comprising, a gas distributing manifold having first and second ports, adapter means for guiding gas between said manifold and the respiratory tract of said subject, first conduit means connected with said first port to supply input gas through said manifold to said subject, an adjustable gas regulating device connected in said conduit means to regulate said input gas to thereby quantitatively control a bodily state of functioning of said subject, second conduit means connected with said second port, a gas analyzer device connected in said second conduit means to receive output gas from said subject by way of said manifold, said analyzer device being adapted by automatically analyzing said output gas to produce signals indicative of the bodily response of said subject to said input gas, and automatic means responsive to said signals for adjusting said regulating mechanism to render said bodily state of functioning of said subject accordant with a preselected standard therefor.

11. Apparatus for furnishing a living subject with respirable gas in the nature of input gas and output gas during, respectively, the inhalations and exhalations of said subject, said apparatus comprising, a gas distributing manifold having first and second ports, adapter means for guiding gas between said manifold and the respiratory tract of said subject, first conduit means connected with said second port to supply input gas by way of said manifold to said subject, an adjustable gas regulating device connected in said conduit means to quantitatively control said input gas as to a property thereof serving to quantitatively control a bodily state of functioning of said subject, a gas analyzer device connected in said second conduit means to receive said output gas from said subject by way of said manifold, said analyzer device being adapted to automatically analyze said output gas for a property thereof characterized in quantitative value by short term fluctuations and a longer term trend, said fluctuations and trend being manifested, respectively, within individual exhalations and from exhalation to exhalation, and being, respectively, extraneous to and indicative in degree of the bodily response of said subject to said property of said input gas, said analyzer being further adapted to generate electric signals as the outcome of said analysis, a sampling device operable by repetitively sampling said fluctuations to render said analysis indicative in terms of said signals of said trend dissociated from said fluctuations, electrical means for developing an electrical reference signal representing a preselected standard of value for said property of said output gas, a servo-amplifier responsive to inputs of said analyzer signals and said reference signal for producing an output of an error signal indicative of change in said analyzer signals away from said reference signal, and servo-motor means responsive to said error signal for adjusting said regulating mechanism to produce a restoration of said analyzer signals with said reference signal by the causal sequence described herein as following on said adjustment, said apparatus being accordingly adapted to render said bodily state of functioning of said subject accordant with a preselected standard therefor.

12. Apparatus for furnishing a living subject with respirable gas in the nature of input gas and output gas

during, respectively, the inhalations and exhalations of said subject, said apparatus comprising, a gas distributing manifold having first and second ports, adapter means for guiding gas between said manifold and the respiratory tract of said subject, first conduit means connected with said first port to supply input gas by way of said manifold to said subject, an adjustable gas regulating device connected in said first conduit means to quantitatively control said input gas as to a property thereof serving to quantitatively control a bodily state of functioning of said subject, second conduit means connected with said second port, a gas analyzer device connected in said second conduit means to receive said output gas from said subject by way of said manifold, said analyzer device being adapted to automatically analyze said output gas for a property thereof characterized in quantitative value by short term fluctuations and a longer term trend, said fluctuations and trend being manifested, respectively, within individual exhalations and from exhalation to exhalation, and being, respectively, extraneous to and indicative of the bodily response of said subject to said property of said input gas, said analyzer being further adapted to generate electric signals as the outcome of said analysis, a sampling device operable in timed relation with changeover in respiration of said subject from exhalation to inhalation for rendering said analysis indicative in terms of said signals of an end-of-exhalation sampling of said output gas for said property thereof, said sampling means thereby rendering said signals indicative of said trend dissociated from said fluctuations, electrical means for developing an electrical reference signal having a steady voltage representing a preselected value for said property of said output gas, a servo amplifier responsive to inputs of said analyzer signals, said reference signal, and an alternating chopping signal of fixed frequency and phase for producing an output of an alternating error signal of said frequency and of opposite phases when said analyzer signals change in one and the other direction away from said reference signal, and an electric motor mechanically coupled with said regulator device to adjust the same, electrically coupled with said amplifier to receive said error signal as one input, and electrically coupled to receive an alternating current of said frequency and of fixed phase as another input, said motor being respectively responsive to error signals of opposite phases to produce opposite direction adjustments of said regulator device serving to equalize said analyzer signals with said reference signal, said apparatus being accordingly adapted to automatically render said bodily state of functioning of said subject accordant with a preselected standard therefor.

13. Apparatus for administering respirable gas to a living subject comprising, a source of input gas under pressure, a manifold having an inlet port and an outlet port, adapter means for guiding the flow of gas between said manifold and the respiratory tract of said subject, first conduit means disposed between said source and said inlet port to supply input gas to said manifold, valve means for opening said inlet port, timing means for actuating said valve means to open said inlet port intermittently to thereby induce respirations in said subject consisting of alternate inhalations of input gas responsive to the pressure thereof, and of exhalations of output gas, an adjustable pressure regulator for said input gas disposed in said conduit means between said source and said inlet port, second conduit means connected with said outlet port, an analyzing device connected in said second conduit means and adapted to provide electric signals as a function of the carbon dioxide content of said output gas, sampling means connected in said second conduit means between said manifold and said analyzing device, said sampling means being controlled by said timing means to draw off a sample of the output gas present in said manifold at the end of exhalation and to thereafter discharge said sample into said analyzing means, and auto-

matic means responsive to said signals for adjusting said regulator to maintain a preselected depth of respiration for said subject.

14. Apparatus for administering anaesthetic to a living subject comprising, a manifold having an inlet port and an outlet port, adapter means for guiding gas between said manifold and the respiratory tract of said subject, first conduit means comprised both of a pair of conduits respectively adapted to carry anaesthetic gas and oxygen and of a third conduit connected between said inlet port and both of said pair of conduits to mix said anaesthetic gas and oxygen, the intermixture thereof being the input gas for said subject, an adjustable regulator connected in said conduit carrying anaesthetic gas to meter the amount thereof flowing to said third conduit to thereby control the percentage thereof present in said input gas, second conduit means connected with said outlet port, valve means for directing into said second conduit means the flow of output gas from said subject into said manifold, an analyzer device connected in said second conduit means to generate electric voltage signals as a function of the content of anaesthetic gas in said output gas, electric circuit means adapted to develop a steady reference voltage representing a preselected depth of anaesthesia for said subject, servo-amplifier means responsive to inputs of said analyzer signals and said reference signal to develop an output of an error signal indicative of change in said analyzer signals away from said reference signal, switch means responsive to the pressure drop in said manifold during changeover in the respiration of said subject from exhalation to inhalation to close a circuit for said error signal as a consequence of said pressure drop, said error signal being thus rendered indicative of an end-of-exhalation sampling for said anaesthetic gas content, and a servomotor operable by flow of error signal in said closed circuit to adjust said regulator to produce a restoration of said analyzer signals to conformity with said reference signal by the causal sequence described herein as following on

40 said adjustment.

15. Apparatus for administering a chemical to a patient comprising means for administering the chemical to the patient, means for directly receiving exhalations from the patient and gas analysis means directly communicating therewith for analyzing the undiluted exhalations from the patient, and means actuated by the gas analysis means for controlling the means for administering the chemical to the patient.

16. Apparatus comprising means for administering a therapeutic treatment to a patient, means for directly receiving exhalations from the patient and gas analysis means directly communicating therewith for analyzing the undiluted exhalations from the patient, and means actuated by the gas analysis means for controlling the means for administering the therapeutic treatment to the patient.

17. Apparatus comprising means for supplying an inhalation gas to a patient, means for directly receiving exhalation from a lung of the patient and gas analysis means directly communicating therewith for analyzing the undiluted exhalations from the patient, and means actuated by the gas analysis means for controlling the means for supplying the inhalation gas to the patient.

18. Apparatus comprising means for supplying an inhalation gas to a patient, means for directly receiving exhalations from a lung of a patient and gas analysis means directly communicating therewith for analyzing the undiluted exhalations from the patient, and means actuated by the gas analysis means for automatically controlling the means for supplying the inhalation gas to regulate the composition of the inhalation gas to the patient.

19. Apparatus comprising means for supplying an inhalation gas to a patient, means for directly receiving exhalations from a lung of a patient and gas analysis

means directly communicating therewith for analyzing the undiluted exhalations from the patient, and means actuated by the gas analysis means for controlling the means for supplying the inhalation gas to regulate the composition of an inhalation gas to the patient.

20. Apparatus comprising means for supplying an anesthetic gas to a patient, means for directly receiving exhalation undiluted from a lung of the patient and gas analysis means directly communicating therewith for determining the anesthetic gas content of the exhalation and means actuated by the gas analysis means for controlling the administration of the anesthetic gas by the supply means to the patient.

21. The apparatus of claim 20 in which the gas analysis means analyzes cyclopropane.

22. Apparatus comprising means for administering a therapeutic gas to a patient, means for directly receiving

exhalation from a lung of the patient and gas analysis means directly communicating therewith for analyzing the undiluted exhalation from the patient, and means actuated by the gas analysis means for controlling the means for supplying the therapeutic gas so that administration of the therapeutic gas may be regulated.

23. The apparatus of claim 22 in which the gas analysis means analyzes carbon dioxide.

24. The apparatus of claim 22 in which the gas analysis means analyzes oxygen.
